UNITED STATES PATENT OFFICE.

FREDERICK HERMANN, OF CLEVELAND, OHIO.

FIRE EXTINGUISHER.

Application filed September 23, 1926. Serial No. 137,304.

This invention relates to new and useful improvements in combustion or fire extinguishers and more particularly fire extinguishers of the chemical pressure gas and vapor generating type.

An object of the invention is to provide a fire extinguisher having electric operating means either manually actuated or automatically actuated by thermostatic means for generating and releasing fire extinguishing vapors, and gases, and alarm sounding or indicating means.

In the drawings:

Fig. 1 is a view of the apparatus partly in section and partly diagrammatic.

Fig. 2 is a horizontal sectional view of the fire extinguisher.

Figure 3 is an enlarged detail sectional view of the valve.

Fig. 4 is an enlarged detail sectional view through the cylinder cap showing the spark igniting device.

Fig. 5 is an enlarged sectional view of the automatic temperature switch.

Referring specifically to the drawings, the fire extinguisher comprises a solution tank 5 having a bottom 6 and an annular formed angle flange 7 disposed within the tank near the top thereof. The tank closure 8, having a reinforcing ring 9 is removably secured by bolts 10 to flange 7 with a gasket 11 between, providing a relatively high pressure connection. A cover 12, with a carrying handle 13 and air port 12', has a seating portion 14 adapted to seat on the mouth of tank 5 and is secured by bolts 15 pivoted on brackets 17 on tank 5, the bolts engaging into yokes 18 on cover 12 and are secured by wing nuts 16. An L fitting 19 opening into the tank 40 and disposed near the bottom, has an upwardly extending tube 20 braced near the top thereof by a bracket 21. A rubber hose 22 secured on the end of tube 20 has a nozzle 23 normally closed with a cork 24. The tank closure 8 has an opening 25 therein connecting with a valve 26 secured on the closure. The valve 26 has an inlet 29 and a flanged outlet 27 normally closed by a needle valve 28 seating therein and extending upwardly through a packing gland 30 and a guide bracket 31. A compression spring 32 is provided between guide 31 and a collar 33 on valve stem 28 normally maintaining the valve seated and closed. A lever 34, pivoted as at 35 on bracket 31, is connected as

at 36 to stem 28, the outer flattened end 37 of the lever is positioned under the base of a stem 39 extending through an opening in the cover top and a guide 41, the upper stem end having a thumb button 42. The button 42, when pressed by the operator's thumb, depresses lever end 37 raising stem 28 and opening the valve for purposes to be hereinafter described.

A pressure regulating valve 43 connected to the inlet 29, is connected by a coupling 44 to the valve 45 of a high pressure tank or container 46 charged with liquid CO₂. The tank 46 is detachably secured by straps 47 and wing nuts and bolts 48 on a suitable heat insulating block 49 fastened on the tank closure 8 which may be suitably heat insulated if desired. The pressure in the container 46 may be relieved through safety valve 43, if the container becomes heated.

A cell holder 50, of perforated sheet metal, is centrally mounted on the tank bottom 6, the holder having a perforated bottom 51 spaced from the tank bottom 6. The holder top split as at 52 is provided with ears 53 having a clamping bolt and nut 54 for removably retaining a combustible mixture cell 55.

The cell 55 is filled with a combustible mixture 55' which generates and releases 85 when ignited, fire extinguishing gases. The cell is provided with a liquid tight bolted cap 56 having a threaded outlet 57 with a coil 59 connected thereto by coupling 58. The coil outlet is connected to an outlet fitting 60 on the tank wall. An elbow 61 is connected to fitting 60 with the outside branch turned upward and closed by a cap 62 having a paraffin closed opening 63.

Means for electrically igniting the cell 95 mixture either by thermostats or a manually operated switch, comprises a jump spark device embodied in a screw threaded neck 64 of cap 72 in which is secured a porcelain insulated electrode 65 by a nut 66. The inner 100 cap side carries a tube 67 about electrode 65, the tube 67 having an electrode 68 positioned adjacent electrode 65. A tube 69 has its flanged end connected with a washer 71 by coupling 72 threaded on neck 64. The other end of tube 69 is connected to the tank side wall. A lead wire 73 disposed within the tube 69 is connected to electrode 65 and a plug block 74 on the outer tank side. The electrode 68 is grounded to the plug block 74, 110

A plug 75 inserted in socket block 74 connects electrodes 65 and 68 through wires 76 and 77 to the secondary coil 79, of an ordinary jump spark coil 78 which surrounds a soft iron core 80 having a primary winding 81 thereon connecting with a condenser 82 connected to a vibrator arm 83 and vibrator contact 84. The vibrator contact 84 and primary coil 81 are connected by wires 85 and 86 respectively to the secondary coil 88 of a transformer 87 having the primary coil 89 thereof connected to the leads 90 and 91 of a suitable electric power source such as house lighting system. Fuses 85' and 86' are connected in lines 85 and 86.

The line 85 has one or more thermostats connected thereto and the thermostats 87 are preferably mounted on the ceiling of the room in which the fire extinguisher is located, where the atmosphere of the room is warmest. The thermostat 87 comprises an insulating tube 88 of rubber or other suitable material having a socket 89 mounted therein at one end with an extension 90 to which an end of wire 85 is connected by thumb screw 91. A contact plunger 92 slidably mounted in tube 88 has a cone shaped contact head 93 and a shank 94 extending through the central opening of a washer 97 mounted in tube 88. A collar 95 is pinned near the shank end to which the opposite end of wire 85 is connected by set screw 96. A helical compression spring 99 positioned between the plunger head and washer 97 is adapted to press the plunger head cone 93 when released, into contacting engagement with socket 89 for closing the circuit in line 85. The plunger 92 is normally held out of contact against the compressed spring 99 by means of a ring 100 of bismuth alloy or other suitable alloy metal, positioned between shank collar 95 and washer 97 and retained by a lug 98 on washer 97. The ring 100 will collapse when heated by the surrounding air to a predetermined temperature, allowing the spring 99 to throw the plunger cone 93 into contact with socket contact 89 closing the line circuit.

One or more normally open press button switches 101 are provided on a wire 102 connecting with wire 85 near the secondary 88 of the transformer and wire 85 near contact 84 are located at a convenient point in or outside of the room for manual operation. One or more suitable fire alarms are provided such as electric bell 103 conveniently located and connected by a wire 104 to wire 85 near contact 84 and a wire 105 to wire 86.

The tank 5 is filled with a solution of 75 parts of $(\text{NH}_4)_2\text{CO}_3$ to 100 parts of water H_2O amounting to approximately three gallons the $(\text{NH}_4)_2\text{CO}_3$ containing 35.46% of NH_3 , 45.79% of CO_2 , 18.75% of H_2O and 21% of crystal water of which the 60.25% of NH_3 and CO_2 is the most efficient fire ex-

tinguishing agent, contained in larger proportions than other fire extinguishing solutions.

The container 46 of about .8 oz. capacity is charged with liquid CO_2 up to 2000 lbs. 70 pressure approximately.

The cell 55 is filled with a highly combustible powdered mixture comprising approximately 59 parts of potassium nitrate, 36 parts of sulphur 99½% pure, 4 to 5½ 75 parts of charcoal and one part of iron oxide Fe_2O_3 , the whole weighing approximately six pounds.

When installed the extinguisher may be conveniently located in a room, sitting on a suitable shelf or support with the plug and socket 75 and 74 connected and the thermostat holding the electric circuit open.

In case of fire in the room or outside, the extinguisher may be disconnected from plug 75 and carried near the fire for manual manipulation. The extinguisher is started by pressing down with the thumb of one hand on button 42 depressing lever end 37 and raising and opening needle valve 28, 80 allowing the CO_2 in container 46 to pass under high pressure through valve 45 and 43, needle valve inlet 29 and outlet 27 through port 25 into tank 5, the expanding CO_2 forcing the $(\text{NH}_4)_2\text{CO}_3$ solution out 90 through elbow 19, tube 20, hose 22 and nozzle 23 forcing the cork out. The nozzle 23, which is held in the other hand of the operator, directs the cold solution in a strong 95 relatively far traveling compact jet to the fire. The strength and length of the stream may be varied by the pressure of the thumb on the button 42 opening or closing the needle valve. The extinguisher may be discontinued by releasing the button 42 allowing 100 the spring 32 to close the needle valve and flow of CO_2 .

The freezing point of the $(\text{NH}_4)_2\text{CO}_3$ solution and CO_2 is relatively low, permitting free use without freezing in cold seasons or climates. The fire extinguisher may be operated automatically to extinguish a fire in the room. When the fire heats and raises the temperature of the air in the room to 62° C. or 143° F., the heated bismuth alloy ring 100 of switch 87 collapses, allowing the spring 99 to throw plunger 92 into contact with socket 89 closing an electrical circuit as follows: The house lighting circuit is connected by wires 90 and 91 to the primary 89 of the step down transformer 87, the stepped down induced current flowing from the secondary winding 88 through wire 85, fuse 85', plunger shank 94, head cone 93, socket 89, wire 85, to jump spark coil contact 84, through vibrator arm 83 to the primary coil 81 and out through wire 86 and fuse 86' to the transformer secondary coil again. The current flowing through the shunt circuit of wires 104 and 105 connected 115 120 125 130 135

to wires 85 and 86 sounds the alarm bell 103. The primary winding 81 magnetizes core 80 which disengages vibrator arm 83 from contact 84 breaking the circuit. When the circuit is broken the spring arm engages contact 84 again closing the circuit and repeating the operation over and over again rapidly. The high tension current impulses induced in the secondary winding 79 from the primary 81 produces a rapid series of jump sparks across electrodes 65 and 68 through wires 76 and 77, plug and socket 75 and 74 and wires 73 and 72 to the secondary 74 the grounded connections of electrode 68.

10 The gas outlet 106 on the tank above the liquid level, is sealed by a perforated cap 107, bismuth alloy disc 108 and gasket 109. The jump sparks ignite the highly combustible mixture 55' in cell 55 which burns rapidly, the highly expanding hot vapors and gases therefrom passing through neck 57 coupling 58, coil 59 and out through elbow 61 into the room melting the paraffin seal 63 on the opening of cap 61. The hot cell 25 55 and coil 59 instantly heats the tank solution the expanding fire extinguishing solution vapors melting bismuth alloy disc 108 and passing through cap 107 into the room. The NH_3 gas generated is lighter than air and penetrates to the upper air strata of the room and the CO_2 gas penetrates to the lower air strata. The gases especially the NH_3 also penetrates laterally into crevices and cracks as well as vertically, reaching and extinguishing all burning spots. The present fire extinguishing gases employed have a tendency to sink vertically passing without penetrating into crevices in the walls of buildings. The steam generated also 30 acts as an efficient fire retarder. The fire extinguisher may be started from a distant point by closing push button switch 101 closing the electrical circuit in wire 85, independently of switch 87, through wire 102,

igniting the mixture in cell 55 before described and also sounding the alarm bell 103.

While I have shown and described one embodiment of the invention, obviously various changes in the proportions and details of construction may be made without departing from the spirit and scope of the appended claims.

I claim:

1. A fire extinguisher comprising a tank containing a solution capable of generating fire extinguishing vapors and having a thermostatically sealed discharge outlet for such vapors, a cell in said tank, containing a combustible mixture adapted to produce, by its ignition, generation of such vapors, and electrically operated means extending into said cell for igniting the mixture therein.

2. A fire extinguisher comprising a tank provided with a discharge outlet and containing a solution which will generate fire extinguishing vapors when sufficiently heated, a cell immersed in the solution in said tank containing a combustible mixture for producing such heat by its combustion, and electric means external to the tank and communicating with said mixture for igniting the same, said means including an electric sparker in the cell.

3. A fire extinguisher as set forth in claim 2, said cell being provided with a heating coil receiving the gases produced by the combustion of said mixture, said coil being exposed to the solution in said tank.

4. A fire extinguisher as set forth in claim 2, said cell having a pipe connected to the cell and extending thru the solution, whereby to heat the same by the products of combustion discharged thru the pipe from the cell.

In testimony whereof, I do affix my signature.

FREDERICK HERMANN.
